Filed Sept. 11, 1961, Ser. No. 66,666

Term of patent 14 years

(Cl. D26—13)

FIGURE 1 is a perspective view of a manual control for a motorized hospital bed, showing our new design; FIGURE 2 is a front elevational view;

FIGURE 3 is a view of the manual control partly in side elevation and partly in vertical section taken on line 3—3 of FIGURE 2;

FIGURE 4 is a rear elevational view;

FIGURE 5 is a top plan view; and

FIGURE 6 is a sectional view taken on lines 6—6 of FIGURES 3 and 4.

The essential features of the design are shown in full lines.

This application is a continuation-in-part of our pending application Serial No. D. 64,042 filed February 24, 1961, now abandoned.

We claim:

The ornamental design for a manual control for a motorized hospital bed, substantially as shown and described.
